(57) **CLAIM**

The ornamental design for a tub for bathing, as shown and described.

DESCRIPTION

In a preferred embodiment, the nature of this product is as a plumbing fixture in the form of a bathing tub primary useful for washing the human body.

FIG. 1 is a right, top, front perspective view of a tub for bathing embodying my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a left, top, front perspective view of a tub for bathing according to another embodiment of my new design, the front elevational view thereof being identical to FIG. 3, the rear elevational view thereof being a mirror image of FIG. 6, the bottom plan view thereof being a mirror image of FIG. 7 and the left and right elevational views thereof being mirror images of respective FIGS. 4 and 5; and, FIG. 9 is a top plan view thereof.

The broken line representations of holes in the figures are for the purpose of illustration only, and form no part of the claimed design.
